UNITED STATES PATENT OFFICE.

JOSEPH H. HEDMARK, OF CHICAGO, ILLINOIS.

STEAM-TRAP.

1,095,159.

Specification of Letters Patent. Patented Apr. 28, 1914.

Application filed January 12, 1912. Serial No. 670,803.

To all whom it may concern:

Be it known that I, JOSEPH H. HEDMARK, a citizen of the United States, residing at Chicago, in the county of Cook 5 and State of Illinois, have invented certain new and useful Improvements in Steam-Traps, of which the following is a specification.

This invention relates to traps or devices 10 adapted to receive or collect the water from a steam heating system or apparatus for the purpose of discharging it from the system or returning it to the boiler.

Although it may be adapted for various 15 purposes it is particularly applicable to steam heating systems, and is preferably used in connection with radiators for returning the water of condensation to the boiler and also for permitting the escape of 20 air from the radiators.

The objects of my invention are to provide an exceedingly simple and efficient device of this character which may be manufactured at a low cost; which will effectively 25 serve the purpose of relieving the radiators from air and water; which will provide a sufficient seal so as to prevent the return of air or steam back into the radiator from 30 its return side under certain conditions; which will have a sufficient seal so as to maintain a partial vacuum within its float 35 chamber under other conditions; and in general to provide an improved form of trap or fitting which will also have such other advantages as will appear from the following description.

In the accompanying drawings illustrating 40 my invention, Figure 1 illustrates a radiator with my improved trap shown applied to its return side; Fig. 2 is a vertical sectional view through the trap; Fig. 3 is a horizontal sectional view taken on the line 3—3 of Fig. 2, with parts broken away for convenience in illustration; and Fig. 4 45 is a vertical sectional view showing a slightly modified form of construction.

As indicated in these drawings, 5 represents a radiator or other portion of a steam system from which the water is to be drained. This radiator is connected by 50 means of a short connection 6 with the steam trap 7, from which the return pipe 8 leads to the boiler or to a pump or vacuum producing apparatus. The trap or regulating 55 device 7 comprises a substantially cylindrical body portion 9, having at one side an

inlet pipe or connection 10 which is engaged by the nipple 6. The inlet does not open directly into the side of the receptacle 9 but connects with a channel or passageway 60 11, which extends downwardly to the bottom of the inner chamber 12. The body 9 is provided with a downward projection 13 to receive the outlet pipe 8. A plug 14 is screwed into the upper part of the opening 65 through the projection 13 and is provided with an upwardly extending pipe or tube 15 which passes up through the center of the chamber 12. The plug 14 is also provided with one or more holes 16 for communication 70 between the chamber 12 and the outlet pipe 8. A float 17 fits freely over the tube 15 so that it may move up and down upon the same, this float being provided at the bottom with a ring or disk 18 adapted to 75 fit closely over the upper ends of the holes 16 to make a substantially tight closure. The device is completed by means of a cap 19 which screws into the upper end of the body 9, this opening being sufficiently large 80 to admit the insertion of the plug 14 and also the float 17. The cap 19 preferably extends upward some distance beyond the body portion and is provided at the center with a hole 20 which fits freely over the upper 85 end of the pipe 15, but preferably fits sufficiently close so as to prevent particles of sediment or grease from passing up into the upper end of the tube. The hole through the tube 15 is comparatively small 90 so that it may allow for the leakage of air but will prevent the escape of any considerable quantity of steam. Steam heating systems with which this device may be most satisfactorily used may be roughly divided 95 into vacuum systems and vapor systems. In the former class pumps or equivalent exhausting devices are used in connection with the return pipes for drawing out the air from the radiators and for returning the 100 water to the boiler. In the latter system the return pipes lead directly to the boiler, but the pressure in the system is rarely raised to more than one pound.

The operation of my improved trap as 105 above described when used in connection with the vacuum system is as follows: When steam first begins to enter the radiator, the air therein will be driven into the trap and will be drawn out through the tube 15 by 110 means of the exhausting apparatus. As soon as steam begins to enter the radiator

and condense therein, the water of condensation will flow down into the bottom of the chamber 12 until it covers the lower edge 21 of the wall forming the inner portion of the 5 passageway 11 and will continue to rise until it arrives approximately at the line A—A. During this time, that is as soon as the water has risen above the lower edge 21 the radiator will be substantially sealed from the 10 chamber 12 so that there will be a partial vacuum formed in this chamber above the water, due to the air or vapor being drawn out through the tube 15 by means of the exhausting or vacuum producing apparatus. 15 As soon as the water reaches the line A—A, at which point it is sufficiently high to raise the float 17, the latter will move upward lifting the ring or closure 18 off from the holes 16 and allowing the water to escape until it 20 is lowered a sufficient amount so that the float again falls and the holes 16 are again closed. It will be noted that an important feature of this operation consists in the forming of a partial vacuum in the chamber 12 so 25 that the float will be free to rise and will not be held down by suction against the plug 14. The tube 15 is preferably made sufficiently long so that it will extend some distance above the height to which the water will normally rise in the trap so that the grease or 30 sediment will not be apt to be deposited around the upper end of the tube and will not be apt to enter the tube.

The action of my improved device in a 35 vapor system is quite similar to that above described, but of course there would be no suction or partial vacuum produced in the return pipes in the manner above described. In a vapor system, when the steam first enters the radiator, air will gradually pass out 40 through the tube 15 and then as the steam condenses, water will flow into the trap until it reaches a sufficient height to raise the float when the latter will rise and permit the escape of water. It will be noted that in this 45 instance, the necessity or desirability of trapping the chamber 12 from the intake pipe 10 in order to form a partial vacuum in the chamber and in order to prevent the 50 vacuum pump or apparatus from drawing steam through the trap is not essential. For such systems the downwardly extending passageway 11 or the division wall between the inlet opening and the inner chamber may be 55 dispensed with as shown in Fig. 4. In this instance the inlet 22 opens directly into the side of the casing 23, the other parts being identically the same as above described. The operation will be somewhat similar to 60 that above described, but if the supply to one radiator is shut off and the radiator is allowed to cool while the others remain in operation, a small amount of air or vapor may pass back into the radiator through the 65 pipe 15 as the radiator becomes cool. How-

ever, in the first form of the device such return will be prevented to the extent that sufficient back pressure will be necessary to overcome the seal between the chamber 12 and inlet pipe 10. It will be noted, however, 70 that the hole through the tube 15 is intended to be comparatively small and will only permit the passage of a small quantity of air or vapor.

While I have described my improved trap 75 or relief device in connection with steam heating systems it may also be adapted for other purposes and I do not wish to be limited to this particular use of the same, neither do I wish to be limited to the exact 80 form shown and described, except in so far as pointed out in the following claims in which—

I claim:

1. In a steam trap or the like, the combination of a casing having a suitable inlet and having an outlet in the bottom thereof, a plug fitting in said outlet, said plug being provided with one or more holes therethrough, a tube extending upwardly from 90 said plug to the top of the casing, the plug having a hole forming a continuation of the hole through the tube, a float slidably mounted on said tube, a closure at the bottom of said float for closing said holes and a cap 95 for closing the top of said casing, said cap having a recess adapted to receive the upper end of the tube.

2. In a device of the character set forth, the combination of a casing having an inlet 100 and having an outlet in the bottom thereof, a substantially flat seat in the bottom of said casing, a tube extending upwardly from said seat, the hole through said tube communicating with the outlet, said seat having 105 one or more holes adjacent to the tube, a float slidably mounted on said tube, a closure at the bottom of said float for closing said hole or holes in the seat, and a cap for closing the top of said casing. 110

3. In a steam trap or water return device, the combination of a chamber having an inlet passageway leading to the bottom thereof and adapted to be seated by water, a plug fitting in an opening at the bottom of said chamber, holes through said plug, a ring fitting over said holes and adapted to close the same, a tube extending upwardly from said plug said tube and plug being provided with an opening leading from the top of the chamber to the outlet thereof, a float slidably mounted on said tube and connected with said ring, and a cap for said casing having a recess therein fitting freely over the upper end of said tube. 115

4. In a steam trap, the combination of a casing having an inlet aperture at one side thereof, and an outlet aperture in the bottom, a plug having a flat upper surface fitting in said outlet aperture and having an 120

125

130

upwardly extending tube with an air passageway therethrough said passageway also extending downwardly through the plug and communicating with the outlet of the 5 casing, a cap for said casing, having an opening for receiving the upper end of said tube, the walls around said opening extending down over the tube, said plug also having one or more vertical holes arranged ad-

jacent to said tube, a float slidably mounted 10 on said tube, and a closure having a flat closing surface at the bottom of said float for closing said holes when the float is at its lowermost position.
